UNITED STATES PATENT OFFICE.

ALFRED TAYLOR, OF BROOKLYN, NEW YORK.

IMPROVEMENT IN ALARMS FOR LETTER-BOXES.

Specification forming part of Letters Patent No. 121,218, dated November 21, 1871.

To all whom it may concern:

Be it known that I, ALFRED TAYLOR, of Brooklyn, State of New York, have invented certain Improvement in Letter-Boxes, which I name "Bell Letter-Boxes."

The nature of my invention consists in operating the bell in an alarm letter-box by a lever fixed upon the hinged door, with its free end acting against a hooked bar connected with the bell-hammer, all as hereinafter more fully described.

Figure I is a cut section of the letter-box embodying my invention. Fig. II is a plan view, with the back of the box removed.

A is the entrance, cover, or door to the front side of the letter-box B. The lever C, being attached to the inside of the door A, will, by the pushing of said door or cover into the box, pull

the rod S connected by the elbow-lever D, to which is attached the bell-hammer E. F is a bell, G being the stand or bearer thereof. H is a spring, one end of which is attached to the stand G and the other end to the elbow-lever D. I is a spring for the purpose of holding the catch J of the rod S up to the end of the lever.

What I claim is—

The combination, with the hinged door A of a letter-depository, of the hooked lever C fixed firmly thereto, catch J, spring I, rod S, elbow-lever D, bell F, hammer E, and spring H, all constructed substantially as set forth.

ALFRED TAYLOR.
